UNITED STATES PATENT OFFICE.

SAMUEL W. GAINES, OF SCIO, OREGON.

FLAX-PULLER.

SPECIFICATION forming part of Letters Patent No. 249,921, dated November 22, 1881.

Application filed April 23, 1881. (No model.)

To all whom it may concern:

Be it known that I, SAMUEL W. GAINES, of Scio, in the county of Linn and State of Oregon, have invented a new and useful Improvement 5 in Flax-Pullers, of which the following is a specification.

Figure 1 is a plan view of my improvement. Fig. 2 is a side elevation of the same. Fig. 3 is a sectional elevation of a part of the reel, 10 enlarged.

Similar letters of reference indicate corresponding parts.

The object of this invention is to facilitate the pulling of flax.

15 In the accompanying drawings, A represents the frame of the machine. B are the wheels, which revolve upon the axle C, attached to the rear parts of the side bars of the frame A.

20 To one of the wheels B is attached a gear-wheel, D, the teeth of which mesh into the teeth of a small gear-wheel, E, pivoted to a side bar of the frame A.

To the outer end of the journal of the gear-wheel E is attached a pulley, F, around which 25 passes a chain or other suitable belt, G. The belt G also passes around a pulley, H, attached to the journal of a drum, I, the journals of which revolve in bearings attached to the side bars of the frame A. The drum I is twelve inches (more or less) in diameter, and is covered with wool, cotton, or other suitable material, which is kept in place by a covering of canvas or other suitable material. The

30 drum I is thus covered with a yielding padding, which should be about an inch thick, and which prevents the flax-stalks from being crushed while being pulled. To the other journal of the drum I is attached a pulley, J, around

35 which passes a belt, K. The belt K also passes around a pulley, L, attached to the journal of the reel-shaft M. The pulleys J L are made of the same size, and the belt K is crossed, so that the adjacent parts of the reel and the 40 padded drum will move at the same speed and in the same direction.

To the reel-shaft M are attached radial arms N, which are arranged in pairs, and the outer ends of each pair of arms enter the holes in 45 the reel-bars O. The bars O are secured to

the ends of the arms N by pins P, which pass through the ends of the side arms, N, and through short cross-slots Q in the reel-bars O, so that the said bars will have a play upon the said arms. The bars O are held out by 55 strong spiral springs R placed upon the arms N, with the inner ends resting against the shaft M, or against shoulders or collars formed upon or attached to the arms N, and their outer ends resting against the reel-bars O. 60 The arms N are made of such a length that the bars O will be pushed back about an inch by contact with the padded drum I, against which the said bars are held by the pressure of the springs R. The reel-shaft M revolves in 65 bearings in the ends of the bars S, the other ends of which are secured to the rear parts of the side bars of the frame A. The forward parts of the bars S are slotted longitudinally to receive the standards T, attached to the side bars of the frame A. The bars S and standards T have a number of holes formed through them to receive the pins u, that secure them to each other, so that the reel can be adjusted higher 70 or lower, as may be required.

To the frame A, in the rear of the padded drum I, is attached a platform, V, of zinc or other suitable material, and which is slightly inclined to the rearward, so that the pulled flax, when released from the drum I and the 75 reel-bars O, will slide down the platform V, whence it can be conveniently raked off.

To the rear cross-bar of the frame A is hinged the cross-bar W of the tongue X.

To the rear end of the tongue X is attached 80 a standard, Y, to the rear side of which is hinged a standard, Z, having a small wheel, a, pivoted to its lower end.

To the upper end of the standard Z is attached a lever, b, so that the said standard Z 85 can be conveniently turned upon its hinges to turn the wheel a and guide the machine.

To the rear part of the tongue X is attached the lower end of a standard, c, which is curved 90 forward, and its upper end passes through a keeper attached to or a slot formed in the rear part of the lever d. The middle part of the lever d is pivoted to a standard, e, attached to the rear cross-bar of the frame A, and its forward end is pivoted to the center cross-bar of 95 100

the frame A, or to a short stud attached to the said cross-bar. With this construction, by operating the lever d, the forward end of the frame A can be raised and lowered as the height of the flax to be pulled may require. The lever d, when adjusted, can be secured to the curved standard c by a pin or other convenient fastening.

In using the machine, as it is moved forward o the flax will be clamped between the reel-bars O and the padded drum I, and will be pulled by the said reel and drum and deposited upon the platform V, whence it can be raked off by hand, or by an automatic mechanism connected with and driven from the driving mechanism of the machine.

Having thus fully described my invention, I claim as new and desire to secure by Letters Patent—

1. The combination, with the reel-shaft M, 20 having radial arms N, arranged in pairs, of the spring-held reel-bars O, having holes that receive the outer ends of each pair of arms, and pins P, which pass through said arms and slots Q of said bars, as shown and described. 25

2. In flax-pullers, the drum I, surrounded by wool or cotton covered with canvas, as shown and described.

3. In a flax-puller, the combination, with the frame A and a driving mechanism, of the 30 padded roller I and the reel having spring-pressed bars O, whereby the flax-stalks will be grasped and pulled without being crushed, substantially as herein shown and described.

SAMUEL WASHINGTON GAINES.
